ELECTRIC LAMP OR SIMILAR ARTICLE

Herbert Lagin, Great Neck, N. Y., assignor to Jane Stacey, Inc., New York, N. Y., a corporation of New York

Application May 19, 1955, Serial No. 36,117

Term of patent 14 years

(Cl. D48—20)

Fig. 1 is a front elevational view of an electric lamp showing my new design;

Fig. 2 is a top plan view thereof, the electric cord being omitted for convenience of illustration; and

Fig. 3 is a front elevational view with the shade omitted.

I claim:

The ornamental design for an electric lamp or similar article, as shown.
